HANS K. LORENTZEN, OF NEW YORK, N. Y.

APPARATUS FOR DUPLICATING TYPEWRITTEN MATTER.

1,378,883.

Specification of Letters Patent. Patented May 24, 1921.

Application filed September 17, 1917. Serial No. 191,710.

To all whom it may concern:

Be it known that I, HANS K. LORENTZEN, a subject of the King of Denmark, residing at New York, in the county of New York

5 and State of New York, have invented certain new and useful Improvements in apparatus for Duplicating Typewritten Matter, of which the following is a specification.

This invention relates primarily to apparatus 10 for duplicating typewritten matter, objects of the invention being to provide a machine of this character which will be relatively simple and inexpensive in construction, easy to operate and efficient for the 15 purposes intended.

Briefly stated, the invention comprises an impression member and a carriage arranged to traverse the same, said carriage being constructed to register the sheets and provided 20 with a roller for pressing the sheets down on the impression member during traverse of the carriage.

A special feature is a gage for front-registering the sheets adapted to be brought 25 into registering position when the sheets are being positioned on the carriage and to be retracted when the presser roller is lowered onto the sheet.

Other features will become apparent as 30 the specification proceeds.

In the accompanying drawing I have illustrated the invention embodied in a practical concrete form but changes and modifications may be made without departure 35 from the true spirit and scope of the invention.

Figure 1 of said drawing is a top plan view of the device; Fig. 2 is a side view thereof with the end portions of the base 40 broken away and appearing in section; Fig. 3 is an enlarged broken view of the carriage showing the parts in different positions in dotted and full lines.

The impression member consists in the 45 illustration, of a transfer blanket 5, of gelatinous material, stretched over a bed 6, which is supported on a suitable frame or base 7.

The carriage is made up of side members 50 8, carrying rollers 9 riding on the sides 10, of the frame, said side members being connected by an inclined sheet supporting table 11. The lower end of this inclined table terminates just above the impression surface 55 face and an open space 12 is provided in the carriage adjoining said lower end of

the table to permit the lower end of a sheet laid on the table to rest directly on the impression surface, as indicated in full lines in Fig. 3.

The sheets are brought into proper front register on the impression member by coming into engagement with a front gage 13, which, at the time of feeding in a sheet is lowered close to the impression surface so 60 as to form a stop for the lower edge of the sheet. For the purpose of retracting this gage from its registering position it is shown slidably mounted in slots 14 in the sides of the carriage, inclined away from the 65 impression surface.

The sheets are side-registered by means of a side gage 15, on the table 11, which may be adjustably held in place thereon by being hooked over the upper edge of the 70 table and provided with a clamping screw 16.

17 designates the presser member, shown in the form of a roll journaled at its ends in a frame 18 which is pivoted at 19 between 80 the sides of the carriage, this frame being rocked on its pivots to raise and lower the roller by means of an upstanding handle 20 attached to the frame. The presser roll is disposed above the open space at the 85 foot of the sheet table so as to engage the edge of the sheet registered on the impression surface against the front gage.

The presser roll and front gage are interconnected so that when the roll is lifted 90 the gage will be in position to register the sheets and when the roll is lowered the gage will be retracted out of engagement with the sheet and out of the way of the presser roll. The means for this purpose consists 95 of the elbow levers pivoted at 21 on the sides of the carriage, and forked on their laterally extending arms at 22 to engage the extended journals 23 of the roll and engaging with their dependent arms 24 in 100 seats or slots 25 in the ends of the front gage. It will be seen from this that as the roll is lifted the elbow levers will be rocked to slide the front gage forward and downward on their guides into a registering position and that as the roll is lowered the gage 105 will be withdrawn out of the path of the roll and out of registering position.

In practice, the copy, which has been made in suitable copying ink, is pressed face down 110 on the transfer surface. This leaves the desired impression on the transfer surface.

The carriage is then drawn to the left, in the drawing, as by means of the handle 20, which serves to thus also simultaneously lift the roll and place the front gage in operative position. A sheet is then positioned on the carriage with its side edge registered against the side gage, which previously has been set to the proper position, and its front edge registered against the lowered front gage. 5 In this position the lower edge of the sheet bears on the impression surface. The roll is now lowered onto this front edge portion of the sheet, the front gage being retracted during this step, and the carriage is pushed 10 forward over the bed. During this movement the roll presses successive portions of the sheet down onto the impression member causing the sheet to receive a gradual even impression. The forward or impression movement is stopped before the end of 15 the sheet passes off the table so that upon a reverse movement of the carriage the impressed sheet will be stripped off the impression member. The handle 20 may be 20 conveniently used for producing both the traversing movements of the carriage and the raising and lowering movements of the roll. Springs 26 may be provided for holding 25 the roll yieldingly down on the impression member, these springs being shown as carried by the sides of the carriage and bearing on the projected journals of the roll.

The operation of the device is so simple as 35 to require no special skill and it will be noted that there are no complicated or delicate parts to get out of order. The number of impressions possible from a given copy will depend upon the character of the transfer left on the transfer surface, and fresh transfer surfaces are provided as needed by winding the transfer blanket in one direction or the other on the supporting rolls 27 as usual in this class of machines.

40 I claim:

1. Duplicating apparatus comprising an impression member, a carriage traversing the same, means for side registering a sheet on the carriage, a slideable front register on the carriage, a presser member on the carriage, means for lowering and raising said presser member and means coacting with said front register and the presser member for sliding the said register out of or into registering 45 position according to the lowering and raising of said presser member.

2. Duplicating apparatus comprising an impression member, a carriage traversing the same, slideable means on said carriage for 50 registering a sheet with the front portion thereof resting on the impression member, a presser roller on the carriage for pressing said front portion and successive portions of the sheet down on the impression member, 55 means for lifting and lowering said presser

roller with respect to the impression member, and means for simultaneously sliding the front register into or out of operative position according to the lifting or lowering of the presser roller. 70

3. Duplicating apparatus comprising an impression member, a carriage traversing the same and provided with an inclined sheet supporting table terminating at its lower end in position to permit a sheet thereon to bear on the impression member, a front register slidably mounted on the carriage, a roller adjacent said lower end of the sheet table, and means for lifting and for lowering said roller onto the portion of 80 the sheet resting on the impression member and for shifting the register.

4. In combination, an impression member, a carriage traversing the same provided with an inclined sheet supporting table and 85 having an open space adjoining the lower end of the table to permit the lower portion of a sheet on the table to rest on the impression member, a slideable register mounted on the carriage, a vertically movable roller 90 mounted in the carriage above said open space, and means pivoted on the carriage for lifting and lowering said roller and shifting the register.

5. In combination, an impression member, a carriage traversing the same provided with an inclined sheet supporting table and having an open space adjoining the lower end of the table to permit the lower portion of a sheet on the table to rest on the 100 impression member, a vertically movable roller mounted in the carriage above said open space, means for lifting and lowering said roller, a movable sheet gage slidably mounted on the carriage and working in 105 said open space below the roller, and means having connection with the roller for retracting said gage out of the path of the roller when said roller is lowered.

6. In combination with an impression member and a horizontally traversing carriage, a side sheet register on the carriage, a horizontally slideable front gage on the carriage, a vertically movable roller on the carriage above the front gage, and means 115 connecting the roller with the front gage for simultaneously sliding the front gage into or out of operative position according to the vertical movements of the roller on the carriage. 120

7. In combination with an impression member, a carriage traversing the same and provided with an inclined sheet supporting table terminating short of the impression member to permit the lower edge portion 125 of a sheet thereon to rest on the impression member, a front gage for registering the front edge of such a sheet, co-operating guides on the carriage and front gage inclined with respect to the impression mem- 130

ber, a vertically movable presser roller mounted in the carriage above the front gage, operating means for lifting and lowering said roller, and connections from said 5 operating means for shifting the front gage.

8. Duplicating apparatus comprising a bed for supporting a transfer surface, a carriage traversing said bed and having up-standing side walls above said transfer surface, 10 an inclined sheet table carried by said side walls, a side gage on said table, a front gage adjacent the lower end of the table, the side walls of the carriage having guide

slots receiving the front gage and inclined with respect to transfer surface, a frame 15 pivoted between said side walls, a presser roller mounted in said frame and having protruding journals at opposite ends of the frame, a handle for raising and lowering the roller frame and elbow levers pivoted 20 on the side walls of the carriage each engaging a roller journal at one end and the front gage at its opposite end.

In testimony whereof I affix my signature.

HANS K. LORENTZEN.
